G. S. HARRIS,
BUILDER MOTION.
APPLICATION FILED MAY 5, 1914.

1,246,814.

Patented Nov. 13, 1917.

UNITED STATES PATENT OFFICE.

GEORGE S. HARRIS, OF WEST POINT, GEORGIA, ASSIGNOR, BY MESNE ASSIGNMENTS, TO DRAPER CORPORATION, OF HOPEDALE, MASSACHUSETTS, A CORPORATION OF MAINE.

BUILDER-MOTION.

1,246,814.

Specification of Letters Patent. Patented Nov. 13, 1917.

Application filed May 5, 1914. Serial No. 836,391.

To all whom it may concern:

Be it known that I, GEORGE S. HARRIS, a citizen of the United States, residing at West Point, in the county of Troup and 5 State of Georgia, have invented certain new and useful Improvements in Builder-Motions; and I do hereby declare the following to be a full, clear, and exact description of the invention, such as will enable others, 10 skilled in the art to which it appertains, to make and use the same.

The invention to be hereinafter described relates to spinning or winding machines, and more particularly to the builder motions employed in such machines for giving 15 to the yarn a distinctive traverse during certain preliminary windings to form a "bunch" and upon the substantial completion thereof to automatically resume the regular traverse to complete the load upon the bobbin.

Various forms of mechanism have heretofore been devised to provide a bunch upon the bobbin near the base portion thereof and 25 then to build up the bobbin with a regular traverse, and an example of such mechanism is found in the prior patent to George S. Harris, No. 1,167,168, dated January 4, 1916, to which reference may be had. It is desirable in some kinds of wound bobbins, that 30 the bunch be formed by relatively short traverses of the yarn until the bunch has assumed the desired size, and that then the yarn traverse be modified so as to merge 35 into the service wind which is finally attained and continued until the bobbin is fully wound.

An important feature of the present invention, therefore, consists in efficiently controlling the traverse of the ring-rail or yarn guide, for producing a feeler bunch at or 40 near the base of the bobbin and then building up the bobbin in the regular manner.

Another important feature of the invention 45 consists in imparting the bunch builder movements to the ring-rail or yarn guide by a rigid member interposed between the builder motion devices and ring-rail traversing devices, and automatically rendering 50 said rigid member inoperative, when the bunch is completed.

Other features of the invention in addition to the above will be hereinafter described in connection with the accompanying drawings which illustrate one good 55

practical form of the invention, it being understood that changes in the means shown may be made within the true scope of the invention as defined by the claims.

In the accompanying drawings:— 60

Figure 1 is a detail, fragmentary view in side elevation of a builder mechanism, part of the spinning frame being seen in section;

Fig. 2 is an enlarged, fragmentary, detail 65 plan view of the motion transmitting pulley or drum and connected parts;

Fig. 3 is a view in side elevation of the pulley or drum and connected parts;

Fig. 4 is a fragmentary section taken on 70 the plane indicated by line 4—4 of Fig. 1, parts being seen in plan.

Referring to the drawing by numerals, 1 indicates the frame of the machine to which is fixed a bracket 2, in which is journaled 75 a pulley or drum 3. A builder motion let-off mechanism, not illustrated, but of any ordinary type, such as that shown in the patent hereinbefore mentioned, has its chain cable 6 extending and fixed to the pulley or drum 3, and a builder chain cable 7 laps that portion of cable 6 wrapped about pulley or chain 3, and the cable 7 is also fixed to the pulley or drum so that the longitudinal reciprocating movement of the cable 6 as determined by the builder motion devices is imparted as an oscillatory movement to the pulley or drum and therefrom to the cable 7 as a reciprocating movement. Cable 7 engages the usual quadrant 8 carried by the 80 arm 9 which is fixed to the shaft 10. The shaft 10 is engaged by an arm 11 provided with a counter-balance weight 12, and the shaft also carries a pusher rod lever 13 engaging the pusher rod 14, which in turn, engages the yarn guide or ring rail 15. The structure thus far described is of ordinary form and the operation is well known, consisting in the swinging of the quadrant 8 by the cable 7, the weight 12 causing an oscillation of the shaft 10 when permitted by the movement of the cable 7, and the cable itself 85 imparting the return oscillation to the shaft 10, so that the ring-rail 15 is lifted by the action of the weight 12 and is lowered by 90 gravity through lack of support by the rod 14 when the weight 12 is being lifted by the action of the cable 7. The common practice 95 of effecting a uniform reciprocation of the cable 7 so that the distance traveled by the 100

105 gravity through lack of support by the rod 14 when the weight 12 is being lifted by the action of the cable 7. The common practice 110 of effecting a uniform reciprocation of the cable 7 so that the distance traveled by the 110

ring-rail 15 at any one time is the same as at all other times is well understood, and it is also understood that the builder motion let-off devices in addition to imparting the 5 reciprocations which produce the uniform traverse of ring-rail 15 also releases a portion of the cable 6 with each reciprocation, which, through the action of the pulley or drum 3, lets off a portion of the cable 7 so 10 that the weight 12 descends a little farther with each stroke than with the preceding stroke, and ascends a proportionately less distance so that the ring-rail 15 makes a gain at each stroke, as well understood.

15 A bracket or arm 16 is fixed to the arm 9 and is provided at its upper portion with a longitudinal slot 17' through which extends the bolt 17 which bolt also extends through a slot 18 in a link or rigid member 19. The 20 bolt 17 is engaged by a nut at its outer end and at its inner portion is formed with an integral or fixed flange 17^a engaging the bracket or arm 16 for enabling the nut to clamp the bolt at any point of adjustment 25 along the slot 17'. A stud or portion 17^b extends inwardly from the inner face of the flange 17^a through the slot 18 of a link 19, and a washer 17^c engages the inner face of the link or rigid member 19 for preventing the link from becoming displaced, a set 30 screw 17^d engaging and retaining the washer in position. The link 19 is a rigid rod or bar and extends from the pin 17 past the pulley or drum. Preferably, the link 19 is 35 formed of two lapping sections, one having slots 19' and the other carrying bolts 19'' which extend through the slots for rigidly clamping the two sections together at any desired point of adjustment. This adjustment 40 enables variations in the length of the link 19 corresponding with variations in the length of the chain 7, due to adjustments or wear thereof, and the pin-and-slot connection of the parts of the link 19 also facilitate 45 accurate adjustment of a new link to an old machine. The free end portion of the link or rigid member 19 is supported by the pin 20 extending laterally from the face of the pulley or drum 3. A notch 21 is formed in 50 the lower edge of the link or rigid member 19 in position for at times receiving the pin 20. A spring 22 is fixed to the bracket 16 and engages the link 19 and is tensioned to exert pressure longitudinally of the link to- 55 ward the bolt 17. The weight 12 is proportioned to exert force sufficiently exceeding the force of the spring 22 to insure retention of the bolt 17 at the right hand end of the slot 18 so long as the pin 20 is engaged in the 60 notch 21. The pin 20 and notch 21 may be formed as desired, but a particularly efficient construction of these parts is the provision of a box sleeve 20' for the pin 20, (seen in Fig. 3) and a squared shape for the notch 65 21 corresponding to the angular formation of

the exterior of the sleeve 20' so that whenever the lower edge of the link 19 passes the plane of the axis of the pin 20, the sleeve 20' will revolve as the link 19 is drawn longitudinally by the springs 22. This occurs 70 only after the completion of the "bunch"

The pulley or drum 3 carries a release member consisting of a plate 23 having a longitudinal slot 24 through which extends retaining bolts 25 adapted to clamp the plate 75 against the face of the pulley or drum 3 at any desired point of adjustment. One end of the plate 23 is beveled to form an inclined surface 27 adapted to engage the overhanging portion of the link 19 after the pulley or drum 3 has acquired a given amount of gain (when the bunch is completed) and to thereupon lift the free end of the link 19 for disengaging the notch 21 from the pin 20. The link, being thus left free, will be 80 pulled longitudinally back by the spring 22 a distance sufficient for carrying the notch 21 back away from the pin 20, so as to prevent the notch 21 from again engaging the pin 20 on the returning movement thereof. 85 The link is of sufficient length beyond the notch 21 to slide on the sleeve 20' of the pin 20 after the notch 21 has been pulled back out of the path of the pin 20 by the spring 22. This movement of the link 19 is accommodated by the slot 18. 90

Thus in operation, in winding a traverse down for doffing the full bobbins, the rail 15 is depressed below the starting point by manually depressing the lever 13 and 100 the lifting rod 14, which produces a longitudinal thrust of the link 19 in a direction to the left, Fig. 1, for moving the notch 21 into engagement with the pin 20. When the notch 21 has engaged the pin 20, 105 and the wound bobbins have been doffed, the lever 13 is released, and the weight 12 thereupon drops, thereby elevating the guide or ring-rail 15 to the starting point, and placing the spring 22 under tension by moving the pin 17 to the rear end of the slot 18. At the beginning of the next spinning operation, the link or rigid member 19 will control the traverse of the ring-rail 15 with 110 each stroke of the builder mechanism let-off, thereby allowing the cable 7 to remain slack and sag, until the part 27 of the plate 23 strikes the link and releases the engagement of the notch 21 with the pin 20. During the restricted movement, the short traverse necessary for building the "bunch" is had and this restriction in the traverse of the ring-rail is due to the fact that the transmission of motion is through a shorter radius on the pulley or drum 3 and a longer radius on the quadrant 8. The length of the traverse, therefore, can be varied by adjustment of the bolt 17 along the slot 17'. As soon as the link 19 is lifted by the plate 23 so 115 that the notch 21 is freed from the pin 20, 120

125 130

the control of the quadrant is restored to the flexible connection or cable 7 and its connected pulley or drum 3 and winding continues under such control until the bobbins are 5 completely wound. The notch 21 will not again engage the pin 20 until the link 19 is manually thrust forward by the depressing lever 13 as above explained.

When it is desired to vary the length of 10 traverse during the bunch-building period, it is necessary only to adjust the bolt 17 along the slot 17', movement of the bolt upwardly in the slot decreasing the length of traverse, and adjustment of the bolt down 15 the slot increasing the length of traverse.

A bracket 26 is provided and formed with a slot 26' through which the link 19 extends, so as to serve as a guide for the link. The bracket 26 is adjustably fixed in place by a 20 retaining bolt 2' extending through the slot 2" in the bracket 26 and engaging bracket 2.

What I claim is:—

1. In a machine of the character described, the combination of builder motion devices, a 25 yarn guide or ring-rail, and operating connections between said devices and rail comprising a motion transmitting pulley or drum, a quadrant, a flexible connection between the quadrant and pulley or drum, a 30 rigid member for rigidly connecting the pulley or drum and quadrant during the building of a bunch, and means for interrupting the rigid connection between the pulley or drum and quadrant when the 35 bunch has been completed.

2. In a machine of the character described, the combination of a ring-rail and builder motion devices, a drum or pulley between the rail and devices, a connection 40 between the drum or pulley and ring-rail including a flexible member, a rigid member for rigidly connecting the drum or pulley and ring-rail during the building of a bunch, and means for automatically disconnecting the rigid member from one of said parts 45 after the bunch has been wound.

3. In a machine of the character described, the combination of a ring-rail and builder motion devices, a pulley or drum and 50 motion transmitting quadrant between the ring-rail and builder motion devices, a flexible connection between the quadrant and pulley or drum, a rigid member connected to the quadrant, means for detachably connecting the rigid member with the drum or pulley, and means for disconnecting the rigid member from the drum or quadrant automatically after the bunch has been wound. 55

4. In builder mechanism, the combination 60 with a pulley or drum, yarn guiding means, and a cable actuated by the pulley or drum for actuating the yarn guiding means, of a rigid link connected to confine movements of the cable, the link having a detachable 65 engagement with the pulley or drum, and

a spring engaging the link for withdrawing the link from such engagement when released therefrom.

5. In builder mechanism, the combination 70 with yarn guide actuating means, a cable for operating said actuating means, and a pulley or drum for actuating the cable, of a rigid link pivotally connected to the yarn guide actuating means and extending to the pulley or drum, the link being formed with 75 a notch, and means connected to the pulley or drum extending into the notch for detachably connecting the link to the pulley or drum.

6. In builder mechanism, the combination 80 with yarn guide actuating means, a cable for operating said actuating means, and a pulley or drum for actuating the cable, of a link pivotally engaging the actuating means, the link having a notch, a pin extending from the pulley or drum into the notch, and means for retracting the link for moving the notch out of the line of the pin when the link is moved to a position releasing engagement between the pin and notch. 85

7. In builder mechanism, the combination 90 with yarn guide actuating means, a cable for operating said actuating means, and a pulley or drum for actuating the cable, of a link connected to the yarn guide actuating 95 means and extending to the pulley or drum, means of engagement between the link and pulley or drum, and a plate connected to the pulley or drum and disposed to have a path of movement intersected by the link for 100 causing the plate to strike the link during movements of the pulley or drum for disconnecting the engagement between the link and pulley or drum.

8. In builder mechanism, the combination 105 with yarn guide actuating means, a cable for operating said actuating means, and a pulley or drum for actuating the cable, of a link connected to the yarn guide actuating means and extending to the pulley or drum, 110 means of engagement between the link and pulley or drum, and a plate adjustably connected to the pulley or drum and disposed to have a path of movement intersected by the link for causing the plate to strike the link during movements of the pulley or drum for disconnecting the engagement between the link and pulley or drum. 115

9. In builder mechanism, the combination 120 with yarn guide actuating means, a cable for operating said actuating means, and a pulley or drum for actuating the cable, of a link adjustably connected with the yarn guide actuating means, and means of detachable engagement between the link and pulley or 125 drum.

10. In builder mechanism, the combination 130 with yarn guide actuating means, a cable for operating said actuating means, and a pulley or drum for actuating the

cable, of a bracket fixed to the actuating means, a link, a pivot for the link having an adjustable engagement with the bracket, and means of detachable engagement between the link and pulley or drum.

11. In builder mechanism, the combination with yarn guide actuating means, a cable for operating said actuating means, a pulley or drum for actuating the cable, and means for oscillating the pulley or drum, of a bracket fixed to and upstanding from the yarn guide actuating means and having a longitudinal slot, a bolt adjustable in said slot and having means of engagement with the bracket for being retained in given adjusted positions, a link pivotally mounted on said bolt and extending to the pulley or drum, and means of detachable engagement between the link and pulley or drum.

12. In builder mechanism, the combination with yarn guide actuating means, a cable for operating said actuating means, and a pulley or drum for actuating the cable, of a pivot carried by the yarn guide actuating means, a link having a longitudinal slot engaging said pivot, the link extending from the pivot to the pulley or drum, and means of detachable connection between the link and pulley or drum.

13. In builder mechanism, the combination with yarn guide actuating means, a cable for operating said actuating means, and a pulley or drum for actuating the cable, of a link pivotally connected to the yarn guide actuating means, means of detachable engagement between the link and pulley or drum, and a guide confining movement of the link.

14. In a machine of the character described, the combination of a ring-rail, a lever for raising and lowering the ring-rail, a drum or pulley, a flexible connection between the drum or pulley and the lever for controlling the movements of the lever during the laying of the main or service windings upon the receivers, a rigid member having a notch, a part adapted to be engaged by the notch of the rigid member to render the rigid member effective in controlling the movement of the lever during the preliminary or bunch windings, and means for automatically effecting disengagement of the notch from said part when the preliminary or bunch windings have been completed to render the rigid member ineffective to move the lever.

15. In builder mechanism, the combination with yarn guide actuating means, a cable for operating said actuating means, and a pulley or drum for actuating the cable, of a link pivotally connected to the yarn guide actuating means, means of detachable engagement between the link and pulley or drum, and a slotted guiding bracket dis-

posed with the link extending through the slot for confining movements of the link.

16. In builder mechanism, the combination with yarn guide actuating means, a cable for operating said actuating means, and a pulley or drum actuated by the cable, of a pin carried by the pulley or drum, a sleeve rotatably mounted on the pin and having a rectangular exterior, and a link pivotally connected to the yarn guide actuating means and extending to the pulley or drum, the link having a rectangular notch disposed to engage said sleeve.

17. In a machine of the character described, the combination of a ring-rail, a lever for raising and lowering the ring-rail, a drum or pulley, a flexible connection between the drum or pulley, and the lever for controlling the movements of the lever during the laying of the main or service windings upon the receivers, a rigid member having a notch, a part adapted to be engaged by the notch of the rigid member to render the rigid member effective in controlling the movement of the lever during the preliminary or bunch windings, and means for automatically effecting disengagement of the notch from said part when the preliminary or bunch windings have been completed to render the rigid member ineffective to move the lever, said means being adjustable to vary the time of disengagement of the notch and said part.

18. In a machine of the character described, the combination of a ring-rail, a lever for raising and lowering the ring-rail, a drum or pulley, a flexible connection between the drum or pulley and the lever for controlling the movements of the lever during the laying of the main or service windings upon the receivers, a rigid member adjustable in length having a notch, a part adapted to be engaged by the notch of the rigid member to render the rigid member effective in controlling the movement of the lever during the preliminary or bunch windings, and means for automatically effecting disengagement of the notch from said part when the preliminary or bunch windings have been completed to render the rigid member ineffective to move the lever.

19. In a machine of the class described, the combination with a ring-rail, of a rigid member for giving the ring-rail a traversing movement to effect the laying of preliminary or bunch windings on a yarn receiver, actuating means for said rigid member, means including a flexible member for giving the ring-rail a traversing movement to lay main or service windings, and means for automatically disengaging the rigid member from one of the parts connected by it to render the rigid member inoperative when the preliminary or bunch windings have been completed.

20. In a machine of the class described, the combination of a ring-rail, a rigid member, actuating means for reciprocating the rigid member for giving to the ring-rail a
5 traversing movement to effect the laying of preliminary windings upon a yarn receiver, and means for automatically disengaging the rigid member from motion transmission connection between the actuating means and
10 ring-rail.

21. In a machine of the class described, the combination of a ring-rail, a lever for raising and lowering the ring-rail, a rigid member having a notch, actuating means for
15 transmitting through the rigid member a

traversing movement to the ring-rail for laying preliminary or bunch windings, means for engaging the notch of the rigid member to establish operative connection between the actuating means and lever 20 through the rigid connection, and a device for disengaging the notch from said engaging means when the preliminary or bunch windings are completed.

In testimony whereof I affix my signature 25
in presence of two witnesses.

GEORGE S. HARRIS.
